CAN TAPPER AND LIQUID DISPENSER UNIT

Charles W. Dunn, Lovington, N. Mex., assignor
of forty per cent to John W. Williamson, Lov-
ington, N. Mex.

Application April 14, 1952, Serial No. 282,095

1 Claim. (Cl. 222—82)

1

The present invention relates to a can tapper and liquid dispenser unit and it consists in the combinations, constructions and arrangements of parts herein described and claimed.

Generally there is provided a device which is unitary in character and which is equipped to be forced into the top of a can containing, for example, lubricating oil and, when so inserted, to latch thereto by means of a handle portion forming a part of the invention. There is also provided as a part of the unit a pump mechanism having a handle which is operable by the thumb of the hand grasping the first-named handle and which pump is equipped with a novel safety valve whereby oil or the like may not be spilled from the can in the event of an accidental tipping thereof but which permits the passage of oil when the same is pumped from the can. Another novel feature of the invention is the disposition of the pump within the can so that a maximum quantity of fluid may be dispensed therefrom.

It is accordingly an object of the invention to provide a novel unitary can punch and liquid dispenser mechanism.

Another object of the invention is to provide a device of the character set forth which is simple in construction, inexpensive to manufacture and yet effective and efficient in use.

Another object of the invention is to provide, in a device of the character set forth, novel means for attaching the same to a can.

A further object of the invention is to provide, in a device of the character set forth, a novel safety valve forming a part of the invention.

Other and further objects of the invention will become apparent from a reading of the following specification taken in conjunction with the drawing, in which:

Figure 1 is a side elevational view, partly broken away, of an embodiment of the invention, 40

Figure 2 is a fragmentary plan view thereof,

Figure 3 is a sectional view, partly broken away, taken along line 3—3 of Figure 1,

Figure 4 is a plan view of a pattern fitting forming a part of the invention,

Figure 5 is a sectional view taken along line 5—5 of Figure 4,

Figure 6 is a perspective view of the device forming the present invention,

Figure 7 is a fragmentary vertical sectional view, partly in elevation, of the device shown in Figure 6,

Figure 8 is an enlarged fragmentary sectional view illustrating certain valves forming a part of a pump constituting a part of the invention, 55 and

2

Figure 9 is an enlarged fragmentary sectional view, partly in elevation, illustrating a safety valve forming a part of the invention.

Referring more particularly to the drawing, 5 there is shown therein a unitary can punch and dispenser unit comprising an elongated hollow cylindrical pump housing 10 cut on a bias at its lower end to provide a punch blade, as indicated at 11, and having affixed adjacent its upper end 16 an angularly disposed plate 12 to the outer end of which there is hinged, as indicated at 13, a supporting handle generally indicated at 14.

The inner end of the handle 14 extends downwardly, as indicated at 15, whereby to abut an 15 upper portion of a dispensing can 16 when used in connection therewith. The handle 14 is provided with an inner serrated face, as indicated at 17, and the lower end has integrally formed therewith an upwardly extending latch hook 18 which is adapted to engage beneath the lower rim of the can 16.

The upper end of the housing 10 has threaded thereon a cap 19 having a stuffing gland 20 mounted therein and which is adapted to abut the upper edge of the housing 10.

Slidably extending through the cap 19 and downwardly into the housing 10 is an elongated plunger rod 21 having a valved piston generally indicated at 22 at the lower end thereof. The piston 22 is provided with an apertured head 23 of leather or the like, the aperture 24 thereof being governed by a ball valve 25 seated thereon by a compression spring 26 mounted in the piston head 23 and controlling outwardly extending 35 passages 27. An inlet valve structure, generally indicated at 28, is mounted in the lower end of the housing 10 and consists of a body 29 having a centrally disposed opening 30 extending therethrough in which opening is seated a ball valve 31 urged to its seat by a compression spring 32 mounted in the body 29.

The can 16 is conventionally supplied with an indented cover 33 and an indented bottom 34. A rocker rivet 35 is affixed to the plate 12 and 45 serves as a pivotal point for a lever of the bell crank type having an inner arm 36 which is connected by means of nuts 37 or the like to the upper end of the plunger rod 21 and an outer operating arm 37.

An outlet fitting 38 extends from the upper portion of the housing 10 and has connected thereto a flexible tubing 39 having a spout 40 at its outer end. The inner end of the fitting 38 is normally closed by a safety valve 41 which is affixed to the plunger 21 by means of a collar 42 and a compression spring 43 surrounds the

rod 21 and is adapted to bear against the gland 20 at its upper end and against the collar 42 at its lower end. A vent punch 44 is formed as a part of the plate 12 being preferably punched therefrom in the manufacture of the plate 12.

A circular pattern fitting 45 is adapted to be placed upon the cover 33 and has centrally affixed to its upper side a washer 46 formed of felt or the like and comparatively smaller circular washer 47 adjacent its peripheral edge and likewise atop the same.

In operation, it will be apparent that when it is desired to dispense the contents of a can 16, it is only necessary to grasp the device forming the present invention and which is illustrated, for example, in Figure 6 of the drawings and thereafter to force the same downwardly upon the cover 33 through an opening 48 defined by the inner edges of the washer 46 so that the housing 10 will extend therethrough and the blade 11 thereof act to puncture the cover 33. Further downward movement of the device with the vent punch 44 aligned with the inner opening 49 defined by the washer 47 will act to form a vent opening, as indicated at 50, in the cover 33, the washers 46 and 47 acting as guides for the blade 11 and vent punch 44 during such operation. Thereupon it will be apparent that the washers 46 and 47 will serve to prevent undue loss of the contents of the can 16. When it is desired to dispense "squirts" of the fluid contained in the can 16, it is only necessary to press downwardly upon the handle 37 whereupon the plunger 21 will be lifted by the arm 36 and fluid forced through the pump and eventually through the fitting 38, the inner end of such fitting 38 being now uncovered by the valve 41. When pressure is released upon the operating handle 37, the spring 43 will force the plunger downwardly to its initial position whereupon the valve 41 will close the inner end of the fitting 38 thus preventing accidental spilling of the contents of the can should the can and the present device be tipped over accidentally. It will also be seen that the device may be easily and securely positioned upon the can 16 by moving the supporting handle 14 downwardly until the hook 18 latches against the bottom 34 and over the lower rim of

the can 16. It will likewise be seen that since the housing 10 is angularly disposed with relation to the plate 12 that when the plate 12 comes to rest upon the upper end of the can as aforesaid and as shown in Figure 7, for example, that the forward lower end of the housing 10 constituting the blade 11 will rest in one corner of the can 16 whereupon when the can is tilted forwardly toward the fitting 38 the maximum amount of fluid contained within the can 16 may be dispensed therefrom.

While but one form of the invention has been shown and described herein, it will be readily apparent to those skilled in the art that many minor modifications may be made without departing from the spirit of the invention or the scope of the appended claim.

What is claimed is:

A device of the character described comprising, in combination with a can, an elongated hollow cylindrical pump housing, a can-punching blade formed on the lower end of said housing, a plate angularly disposed upon the upper portion of said housing, a can vent punch formed in said plate, a can-engaging support handle hinged to the rear of said plate, a fitting in the forward upper portion of said housing, a dispensing tube attached to said fitting, a nozzle at the free end of said tube, a pump in said housing, and a pump lever for said pump pivotally mounted on said plate and having its free end adjacent said support handle, a circular pattern adapted to be affixed to the top of said can, a felt washer centrally affixed to the upper face of said pattern and adapted to receive said housing therethrough, and a felt washer eccentrically affixed to said pattern and adapted to receive said vent punch therethrough.
